JAY M. JOHNSON, OF CHICAGO, ILLINOIS

FARE REGISTER

Application filed March 2, 1931. Serial No. 519,613.

This invention is a novel improvement in fare registers and the like. Its object is to provide a register wherein coins of various denominations, such as nickels, dimes or quarters, may be inserted, and the insertion of such coin will cause the exact number of fares covered by such coin to be registered on a uniform fare basis. If for example the fare is 5¢, then if a nickel is inserted one fare would be registered, if a dime is inserted two fares would be registered, and if a quarter is inserted five fares would be registered. Such registration is accomplished by means of novel coin-actuated counter-actuating mechanism, as hereinafter described, wherein the difference in the diameter of various coins is utilized to vary the operation of the register.

The drawings illustrate one practical embodiment of the invention as designed for a fare register in which 5¢ is the basic fare. In the construction shown in the accompanying drawings and hereinafter described, the insertion of a nickel will cause the mechanism to advance the counter two units forward and then move it backward one unit thereby registering but one fare; the insertion of a dime will cause the mechanism to advance the counter two units, registering two fares; the insertion of a quarter would cause the mechanism to advance the counter two units forward, then move it backward one unit, and then advance it four more units forward thereby registering a total of five fares.

An explanation of the fare register illustrated will enable others to understand the invention and apply it to the other mechanisms in which a register of such character would be useful. The claims following the description summarize the essential features of the invention and the novel constructions and combinations of parts for which protection is desired.

In the drawings:

Fig. 1 is a side view partly broken away of a complete fare register containing one practical embodiment of my invention. Fig. 2 is a top plan view of Fig. 1. Fig. 3 is an enlarged side view of the register mechanism removed from the casing. Fig. 4 is a top plan

view of Fig. 3 partly broken away. Fig. 5 is a front view of Fig. 4 partly broken away. Fig. 6 is a detail plan of the braking devices.

In the embodiment of the invention shown the counter actuating mechanism is contained in a casing C of any suitable construction, having a slot S for the admission of coins.

Within the casing C is arranged the counter actuating mechanism which is the subject of the present invention and which for recording 5¢ fares is constructed as follows.

As the coin enters through slot S it passes between guide plates 1 mounted within the casing, and in so doing passes between a fixed roller or pin 1a mounted between the plates and a roller or pin 2a attached to the upper end of a swingable lever 2, which is pivoted at 2b on the casing. The plates 1 have arcuate slots 11a to permit the desired extent of swinging movement of the lever 2. To this lever is attached a segmental rack 2c which extends beside the adjacent plate 1 and meshes with a pinion 3a fast on a rotatable shaft 3 journaled in a plate 1 and an outer plate 1b, which is fixedly attached to and spaced from such plate 1 by studs or pins 1c.

Fast on shaft 3 adjacent pinion 3a is a cam disk 4 provided with a cam member 4a adapted to engage a laterally projecting cam member 5a on a disk 5 loosely mounted upon the shaft 3 beside cam disk 4. The cam faces are such that when the shaft 3 is turned anti-clockwise the cam members 4a, 5a will cause disk 5 to move axially longitudinally of shaft 3 and away from disk 4. Attached to disk 5 at the side of cam disk 4 is a mutilated gear 5b which has a laterally projecting cam member 5c which is adapted to engage a cam member 6c on a cam disk 6 fast to shaft 3.

When the shaft 3 is rotated anti-clockwise the opposed cam members 4a, 5a will move disk 5 and segment 5b longitudinally of the shaft 3 and move cam member 5c into position to engage cam member 6c in disk 6 on the reverse rotation of shaft 3. When shaft 3 is rotated clockwise the cam member 6c, 5c will cause the disk 5 and segment 5b to move lengthwise of the shaft 3 and return cam member 5a into position to engage member

4a when the shaft 3 is rotated anti-clockwise. The disk 5 and segment 5b are thus alternately shifted on shaft 3 by the action of the cam members for a purpose hereinafter explained.

The mutilated gear 5b when shifted to the position indicated in dotted lines in Fig. 6 is adapted to engage a pinion 7a attached to a shaft 7 journaled in a bearing 1e attached 10 to frame 1b and on this shaft adjacent pinion 7a is a pinion 7b which is controlled by a Geneva or stop gear 6b fixed on shaft 3 adjacent disk 6.

The pinion 7a continually meshes with a 15 pinion 8a on a shaft 8 mounted in the frame; and shaft 8 carries or is connected to the shaft of a counter or register R mounted on a bracket 1f attached to a plate 1, or otherwise suitably mounted in the casing. This counter 20 is properly actuated as hereinafter described each time a coin is inserted in the casing.

The disk 5 has on its face adjacent disk 4 a laterally projecting pin 5s adapted to engage a stop lug or pin 1s on the adjacent member of the frame 1, see Fig. 6. This disk also has on its face adjacent the segments 5b and near its periphery a laterally projecting pin 5p which, if the disk 5 is sufficiently rotated anti-clockwise, will engage the tooth of pinion 7a and turn this pinion two teeth in a direction opposite to that in which it is rotated by the segment 5b as hereinafter explained.

35 The shaft 3 can be rotated clockwise to return the parts to normal position by any suitable means. In the construction shown a drum 3d is fastened to one end of shaft 3, and a cord 3e is wound around the drum and connected to a weight 3f, which may have a bore by which it is slidably guided on a pin 3g attached to the bottom of the casing.

40 Disk 5 and gear 5b being integral are rotated by cams 4 and 6c, being always in engagement with one or the other. When coin is inserted it imparts motion to rack 2e and pinion 3a which pinion is integral with cam 4 thus imparting counter clockwise rotation. 45 Cam 4 pushes disk 5 longitudinally on shaft 3 until gear 5b is in line of engagement with pinion 7a. Continued rotation moves disk 5 and gear 5b until the required number of teeth have taken effect on pinion 7a. For 50 instance a dime moves gear 5b until two teeth have taken effect, counting two on the counter. A nickel will move gear 5b until two teeth have taken effect counting two on counter and still further until the pin 5p has 55 taken effect thus rotating pinion 7a in the opposite direction, thus subtracting one count of the two counts already made. In the case of the quarter two counts are made by gear 5b then one subtracted by pin 5p 60 then four more added by gear 5b.

In the construction shown the pinion 7a has six teeth and the mutilated gear 5b is moved into and out of position to mesh with it. The pinion 7b is fast to pinion 7a and in conjunction with the stop gear 6b acts to 70 position pinion 7a in correct position to be meshed by the teeth of mutilated gear 5b, and by the tooth 5p on disk 5. The pinion 8a being permanently in mesh with pinion 7a transmits the motion of pinion 7a to the 75 rotary counter R, Fig. 2.

To prevent overturning of the disk 5 by momentum any suitable brake may be employed. As shown the opposite faces of the disk 5 are 80 engaged by friction members 9 mounted in the free ends of swingable arms 9a pivoted at 9b on a bracket 1t on the frame or other suitable support. These arms 9a are yieldingly drawn together by a spring 9c, and hold the friction members in contact with the surfaces of the disk. The friction arms 9a while retarding the motion of disk 5 permit the cams to move said disk longitudinally on the shaft 3 and shift mutilated gear 5b in and out of 90 operative position with relation to pinion 7a. To prevent overthrow of the pinion 7a by momentum any suitable brake may be employed. As shown (Fig. 1) a friction drum 7e fast on the shaft 7 is engaged by a flat 95 brake spring 7s fastened to a pin 7p on the plate 1b of the frame.

Operation

A coin can be entered through the coin slot S between the rollers 1a, 2a and after 100 passing the roller 2a on the register actuating lever 2 drops onto a chute C' and is directed onto a hinged door E of the usual construction in rear of a sight glass G where it can be seen by the operator. The door E can be 105 swung back by the finger of the operator to permit the coin to drop into his hand.

In order to pass between the rollers 1a and 110 2a the coin must force lever 2 to the right, and segment 2c meshing with pinion 3a moves it and shaft 3, with the disks 4 and 6 and gear 6b, anti-clockwise. The initial movement of cam disk 4 causes cam members 4a, 5a to move disk 5 and mutilated gear 5b axially on shaft 3 toward the disk 6 until the mutilated gear 5b and tooth 5p are 115 in position to engage with pinion 7a when the disk is rotated; and when gear 7a is turned it imparts motion to the register shaft 8 through pinion 8a. The extent of rotation of pinion 7a (and consequently of the unit wheel of the counter R) by gear 5b depend upon the extent of rotation of the disk 5a and the arrangement and number of teeth upon the mutilated gear 5b.

In the construction shown the teeth on the mutilated gear 5b are so spaced and arranged that if a dime is entered the resultant anti-clockwise movement of shaft 3 will cause gear 5b to move pinion 7a a sufficient 120

number of teeth to advance the register counter two points. If a nickel is entered instead of a dime a greater extent of movement is imparted to disk 5 and gear 5b, and gear 5b is so toothed that on the anti-clockwise rotation thereof it will rotate pinion 7a sufficiently to cause it to first advance the unit wheel of the counter two points, then the gear 5a (being mutilated at this point) 10 frees pinion 7a and while it is so freed the tooth 5p on disk 5a (which has then made about one half of a revolution) engages the pinion 7a at the side opposite the gear 5b and turns pinion 7a backward sufficiently to 15 cause it to reversely operate the shaft 8 and move the counter back one point; and the pin 5p passes on above and clear of the pinion 7a. Then as the nickel drops between the rollers 1a, 2a shaft 3 is moved counter-clockwise 20 by the weight 3f and such movement causes cam member 6c to engage cam member 5e and move gear 5b and disk 5 toward cam member 4; gear 5b moving out of position to mesh with pinion 7a, and tooth 5p out of 25 position to engage the pinion 7a. Gear 5b and disk 5 also rotate clockwise in returning to normal position until disk 5 is arrested by the pin 2a engaging the end of slot 11s, and stop pin 5s engaging stop pin 1s.

30 If a quarter is entered, the disk 5 will be rotated counter-clockwise and moved to bring gear 5b and pin 5p into position to engage with pinion 7a. Then as it moves counter-clockwise the mutilated gear 5b will 35 first mesh with pinion 7a and cause it to advance the counter two points, then gear 5b disengages pinion 7a and pin 5p engages pinion 7a as above described and turns it backward thereby causing the counter to move 40 back one point; then as the disk continues to move anti-clockwise pin 7p clears pinion 7a and other teeth on gear 5b engage pinion 7a and cause it to advance the counter four more points, making a total advance of five points.

45 When the quarter drops into the casing the parts are returned to normal position as above described.

Any suitable means may be provided to prevent retraction of the coin after it has 50 been entered into the slot S. I would preferably use devices such as shown in my companion application for fare collectors (case 7811) filed March 2, 1931, Serial No. 519,614.

It will be obvious to those skilled in the 55 art that the invention is capable of considerable variation in construction, and also that it is adaptable for other coin controlled mechanisms; and therefore I do not consider the invention restricted to the specific use 60 thereof herein described, nor to the specific embodiment thereof illustrated in the drawings.

I claim:

1. In mechanism of the character specified, 65 a counter, a pinion for operating the coun-

ter, an oscillatory shaft, a mutilated gear on the shaft adapted to engage the pinion and cause it to advance the counter, a member also mounted on the shaft adapted to engage the pinion and cause it to set back the 70 counter; coin actuated devices whereby the shaft is turned in the direction to cause the gear and member to operatively engage the pinion; and means for turning the shaft in the opposite direction to return the parts to the normal position.

2. In mechanism of the character specified, a counter, a pinion for operating the counter, an oscillatory shaft, a mutilated gear slidably mounted on the shaft and adapted to engage the pinion and cause it to advance the counter when the shaft is turned in one direction; a member also slidably mounted on the shaft adapted to engage the pinion and cause it to set back the counter; coin actuated devices whereby the shaft is rotated in the direction to cause the gear and member to operatively engage the pinion; and means for 80 rocking the shaft in the opposite direction to return the parts to normal position.

3. In mechanism of the character specified a casing having a coin inlet, a rotatory shaft in the casing, a movable member adapted to be operated by the insertion of a coin and rotate said shaft in one direction, means for rotating the shaft in the opposite direction when the coin has passed, a counter, a rotatable pinion for operating the counter, a mutilated gear on the shaft adapted to engage the pinion in one direction of rotation of the shaft and cause it to advance the counter, and a member operated by the shaft adapted to engage the opposite side of said pinion during the rotation of the shaft to set back the 90 counter.

4. In mechanism of the character specified having a coin inlet, a rotatory shaft, a movable member adapted to be operated by the insertion of a coin and rotate said shaft in one direction, means for rotating the shaft in the opposite direction when the coin has passed, a disk on said shaft, means to shift the disk longitudinally of the shaft, a counter, a rotatable pinion for operating the counter, a mutilated gear adapted to engage the pinion in one direction of rotation of the shaft and cause it to advance the counter, and a member operated by the disk adapted to engage the opposite side of said pinion during the rotation of the disk to set back the 100 counter.

5. In mechanism of the character specified, a casing having a coin inlet, a rotatory shaft, a movable member in the casing adapted to be operated by the insertion of a coin and rotate said shaft in one direction, means for rotating the shaft in the opposite direction when the coin has passed, a disk slidably and rotatably mounted on said shaft and means 110

130

- to shift the disk longitudinally of the shaft, a counter, a rotatable pinion for operating the counter, a mutilated gear operated by the disk adapted to engage the pinion in one direction of rotation of the shaft and cause it to advance the counter, and a pin on the disk adapted to engage the opposite side of said pinion during the rotation of the disk and cause it to set back the counter.
10. 6. In mechanism of the character specified, a casing having a coin inlet, a rotatable shaft, a member adapted to be operated by the insertion of a coin and means connected with said member adapted to rotate said shaft in one direction, means for rotating the shaft in the opposite direction when the coin has passed, and a mutilated gear rotatably mounted on said shaft, cam members fixed on the shaft at opposite sides of the mutilated gear adapted to alternately shift said gear longitudinally of the shaft, a counter, a rotatable pinion adjacent the disk, gearing between the pinion and the counter; said mutilated gear engaging the pinion in one direction of rotation of the shaft and causing it to advance the counter, and a member on the shaft adapted to engage the opposite side of the pinion during the rotation of the disk and cause it to set back the counter.
15. 7. In mechanism of the character specified, a casing having a coin inlet, a rotatable shaft, a movable rack adapted to be operated by the insertion of the coin, a pinion on the shaft engaged by said rack to turn the shaft in one direction when a coin is inserted, means for rotating the shaft in the opposite direction when the coin has passed, a disk slidably and rotatably mounted on said shaft, cam members fixed on the shaft at opposite sides of the disk and adapted to alternately engage the disk to shift it longitudinally of the shaft, a counter, a rotatable pinion adjacent the disk, gearing between the pinion and the counter, a mutilated gear operated by the

disk adapted to engage the pinion in one direction of rotation of the shaft and cause it to advance the counter, and a pin or member on the disk adapted to engage the opposite side of the pinion during the rotation of the disk and set back the counter if the disk rotates beyond a certain number of degrees.

8. In mechanism of the character specified, a casing having a coin inlet slot, a member adjacent the slot adapted to be moved in one direction by the insertion of a coin in the slot, and differentially according to the diameter of the coin, a counter, and mechanism actuated by the differential movement of said movable member whereby the counter is variably actuated in accordance with the value of the coin inserted.

9. In mechanism of the character specified, a casing having a coin inlet slot, a movable member adjacent the slot adapted to be moved in one direction by the insertion of a coin in the slot, the coin actuated movement of the member varying differentially according to the diameter of the coin, spring means for returning the member to normal position after the insertion of the coin; a counter and mechanism actuated by the differential movement of said movable member whereby the counter is variably actuated in accordance with the value of the coin inserted.

10. In mechanism of the character specified, a casing having a coin inlet slot, a movable member adjacent the slot adapted to be moved in one direction by the insertion of a coin in the slot, the coin actuated movement of the member varying differentially according to the diameter of the coin, spring means for retracting the member after the entry of a coin, a counter and gearing operated by the differential movement of said movable member whereby the counter is variably actuated in accordance with the value of the coin inserted.

JAY M. JOHNSON.
